UNITED STATES PATENT OFFICE

158,655

COMBINATION DESK UNIT

Albert S. Freethey, Corpus Christi, Tex.

Application March 31, 1948, Serial No. 145,460

Term of patent 7 years

(Cl. D74—1)

To all whom it may concern:

Be it known, that I, Albert S. Freethey, a citizen of the United States, residing at Corpus Christi, in the county of Neches and State of Texas, have invented a new, original, and ornamental Design for a Combination Desk Unit, of which the following is a specification, reference being had to the accompanying drawing forming a part thereof, wherein:

Fig. 1 is a perspective view of a combination desk unit embodying my new design; and

Fig. 2 is a top plan view of the same.

I claim:

The ornamental design for a combination desk unit, as shown.

ALBERT S. FRETHEY.
